UNITED STATES PATENT OFFICE.

BOYD M. GILLESPIE, OF INDIANAPOLIS, INDIANA.

DEVICE FOR COALING SHIPS.

1,178,849.

Specification of Letters Patent. Patented Apr. 11, 1916.

Application filed March 27, 1914. Serial No. 827,711.

To all whom it may concern:

Be it known that I, BOYD M. GILLESPIE, a citizen of the United States, residing at Indianapolis, in the county of Marion and

5 State of Indiana, have invented new and useful Improvements in Devices for Coal-
ing Ships, of which the following is a specification.

This invention relates to loading apparatus, and particularly to apparatus of this character for coaling ships at docks or like stations; and it has for an object to provide means whereby the maximum amount of coal can be supplied to the ship with a minimum expenditure of labor and in an 10 expeditious manner.

Another object of the invention is the provision of apparatus of this character in which means are employed to prevent the undue scattering of dust during the operation of transferring the coal from the apparatus to the ship or receiving vessel.

Another object of the invention is the provision of apparatus of this character 25 which will consist of a hopper and a super-
posed track structure, the latter being de-
signed to permit of the travel of ordinary
railway dumping cars thereover and the
supporting structure of the track being such
30 that the cars when dumped will cause the
coal to be properly directed to the receiving
hopper.

Another object of the invention is the provision of apparatus of this character 35 which will accommodate itself to various types of cars such as cars in which the bodies thereof are adapted to dump to the side or bodies in which the bottoms thereof are of substantially hopper formation and pro-
40 vided with discharge gates by means of which the contents of the car can be dropped in a vertical direction.

With these and other objects in view, the invention consists of certain novel features 45 of construction, combination and arrangement of parts, as will be hereinafter described and claimed.

In the accompanying drawings:—Figure 1 is a vertical longitudinal section through 50 the apparatus; Fig. 2 is a transverse section therethrough; Fig. 3 is an end view of the apparatus; Fig. 4 is a side view of the discharge chute of the apparatus, showing the protecting shield at the outer end of the chute engaged over the frame of the opening in the hold of the vessel, so as to prevent 55

the scattering of the dust during the transferring operation; Fig. 5 is a similar view, showing the shield adjusted to an inactive position; and Fig. 6 is a section on line 6—6 60 of Fig. 4.

The apparatus consists of a structure 1 in the form of a shed which is provided with a plurality of hoppers 2, 2. At this time it is preferred to mention that each of the said 65 hoppers 2 is of a length which will permit it to accommodate material discharging from a number of cars above the hopper, but each of these hoppers discharges into a common chute 3 which leads to one side of the structure 1, and which is extended at a downward angle from the bottom of the hopper so that the coal will discharge by gravity to the point where it is to be conducted.

Superposed relative of the hoppers 2—2 75 and mounted in the shed or structure 1 is a track structure 4, the rails 5, 5 of which are supported upon cross ties 6, that are mounted at appropriate intervals upon longitudinal beams or supporting girders 7. These 80 girders are supported upon vertical standards 8, which may rise from the bottom of the structure 1 or which may be secured upon the structure in any suitable well known manner. The walls of each of the 85 hoppers 2, 2 merge to a common point, namely, that of the bottom of the hopper, and it is to be assumed that each hopper is to accommodate the material flowing or dis-
charging from four or any desired number of 90 cars. The car shown conventionally at 9 in Fig. 3 is of the tilting body type and when in a discharging position assumes the angle shown in dotted lines in Fig. 2. In order to prevent the undue scattering of the material 95 as it is discharged from the car body to the hopper and with a view to directing the material to the hopper, I provide for each car a pair of deflecting or guard hoods 10, 10 100 respectively arranged at the opposite sides of the track structure. Each of these hoods is provided with an open side 11, an open bottom 12 and a curved deflecting wall 13,

the lower end of the latter being disposed wholly within the plane of the sides of the adjacent hopper 2 of the shed 1. By providing hoods 10, 10 as just referred to, the cars in which some of the bodies tilt in an opposite direction to others will be properly accommodated as will be understood. Each 105 hood has a length sufficiently exceeding that of the car, so that when the body of the lat-

ter is in a dumping position shown in the mentioned dotted lines in Fig. 2, the coal will be housed against being scattered from the ends of the hood.

5 The track structure 4 may be extended through the ends of the shed 1 and it finally finds support upon the ground so that cars from an ordinary track system may be switched onto the track forming a part of 10 this apparatus and the cars then conducted through the door opening 12^a at the end of the shed and run over the structure 4 and positioned with such respect to the hoods 10, 15 that will insure a proper delivery of the coal to the receiving hoppers 2. The door opening 12^a may be closed by sliding doors 13^a, 13^b or any other suitable well known means. Some dumping cars are provided 20 with hopper bars provided with gates or swinging doors that are adapted to be opened so as to permit coal to be discharged in a vertical direction. The space between the rails 5, 5 will accommodate this type of car and the ties 6 are spaced at such distances from each other so as to prevent accumulation of material beneath the cars during 25 the dumping of the material.

The structure herein referred to is intended for the delivery of coal to ships and 30 through the arrangement of the chutes 3 it is seen that their outer ends may be extended into the openings in the hold of the vessel, as shown in Fig. 4. The frame 14 of the opening in the hold or coal bunkers extends 35 usually beyond the side of the vessel, as at 15. In order to prevent the objectionable scattering of the dust created by the discharge of the coal from the hopper of the loading apparatus to the ship I provide each 40 of the chutes 3 with a shield 16 supported upon the chute by a driven axle 17. The chute is provided with a driving axle 18, and the latter carries a sprocket gear 19, which is connected by a chain 20 to a similar

gear 21 on the driven axle 17. The gear 19 45 is provided with manipulating means in the form of a handle 22, which may be operated manually if desired so that the chain 20 can be propelled, and as a consequence thereof the shield 16 may be moved to any of its 50 required positions that may be necessary. The shield is provided with sides 23, 23 of substantially V-form that are adapted to extend downwardly over the sides of the chute when the shield is in the position shown in 55 Fig. 4. The sides 23, 23 are connected by a top wall 24, that is adapted to extend over onto the projecting portion 15 of the frame 14. In this manner the space above the chute and immediately adjacent the frame 14 60 is closed and the flying dust is held against accumulating upon the vessel.

I claim:

In a device of the class described, in combination a hopper, said hopper having 65 spaced longitudinal walls, a longitudinal series of transversely spaced apart bars secured at opposite ends upon the upper edges of said walls, a pair of tracks supported upon said bars longitudinally between the ends of said bars, two longitudinal series of spaced apart hoods, each of said hoods having sector-shaped side walls and a curved back, and having a plurality of said cross bars passing through their curved 75 backs whereby to support the same, the angular corners of the sides of said hoods being disposed in line with said bars whereby the lower ends of said hoods will project into the upper end of the hopper, the corners of 80 said side walls of the hoods being disposed adjacent the rails of said tracks.

In testimony whereof I affix my signature in presence of two witnesses.

BOYD M. GILLESPIE.
